John P. Hileman Inventor

By his Attorneys Thomas Slade &
Frank A. Fouts

UNITED STATES PATENT OFFICE.

JOHN P. HILEMAN, OF ARROWSMITH, ILLINOIS.

HEDGE-TRIMMER.

SPECIFICATION forming part of Letters Patent No. 355,396, dated January 4, 1887.

Application filed March 20, 1886. Serial No. 195,992. (No model.)

To all whom it may concern:
Be it known that I, JOHN P. HILEMAN, of 5
Arrowsmith, McLean county, Illinois, have invented certain new and useful Improvements in
Hedge-Trimming Machines; and I do hereby declare that the following is a full, clear, and exact description thereof, reference being had to the accompanying drawings, and to the letters of reference marked thereon, making a 10
part of this specification.

This invention relates to certain improvements in hedge-trimming machines; and it has for its objects to provide certain improved means whereby the cutting mechanism is operated and controlled, as more fully hereinafter set forth. These objects are attained by the means illustrated in the accompanying drawings, in which—

Figure 1 represents a perspective view of 20
the improved invention, and Fig. 2 represents a top plan view thereof.

In said drawings, the letter A indicates the main frame, constructed preferably of wood, and having side uprights, B, which are connected and braced by a cross-beam, C.

D indicates a master-wheel, which is fastened to the shaft E. On said shaft is mounted a bevel gear-wheel, F. The wheel F gears with a pinion, G, which transmits its motion to 30
the bevel-wheel H, and thence through the pinion I to the shaft K. On this shaft is secured a miter-wheel, L, which gears with a miter-wheel, L'. A crank-wheel, M, is secured to the shaft K.

N is a shaft journaled on the supplemental frame, and having at one end the miter-wheel L, and provided on its other end with crank-wheel N'.

The letter P indicates a horizontal cutter-bar, which operates to cut the top of the hedge; and R, a vertical cutter-bar to cut the side of the hedge, the said cutter-bars being actuated, respectively, by the pitmen S and T. The pitman S is actuated by the crank-wheel M, and the pitman T by the crank-wheel N'.

To render the apparatus adjustable to different heights, I employ a frame-work which is vertically adjustable on the standards B. The cutter-bars and their immediately-attached operating mechanism are also raised and lowered with the adjustable frame.

U U indicate two side parallel bars, notched

at U', so as to slide on the standards B. There are three transverse bars secured to the bars U. These bars are lettered Q Q' Q''. There is also 55
a fourth bar, Q', on the top part of the movable frame, which lies parallel with the side bars, U. There is a series of retaining-plates, E', for holding the shafts K N in position. These plates are secured to the tops of the 60
horizontal bars.

Z is a vertical rotary shaft provided with a collar, Z', which supports it in an opening in a cross-bar, Z''. Said cross-bar has its ends secured to the standards B. The cross-bar Q' 65
is provided with an opening for supporting the shaft Z and holding the same and its wheel H in line. Said shaft is provided on its lower end with a bevel gear-wheel, X, which meshes with the main shaft-wheel F.

V V are two vertical rack-bars, secured at their upper ends to the side bars, U U, of the movable frame. The notches V' on these bars V are engaged by cog-wheels V'' on a shaft, V'. The ends of this shaft are journaled to the side 75
frame-bars, A.

V' are guide-pieces on the inner sides of the frame-pieces A, for holding the rack-bars V in line.

W is a rod for elevating the adjustable frame. 80
This rod is held in position on its lower end by means of an arm, Y, which extends inward from one of the frame-pieces. This arm is provided with an opening for the reception of the rod, said rod being provided with a collar, 85
W', to prevent it from sliding down through the opening in the arm-piece Y. The end of the rod is provided with a worm, W'', which meshes with a worm-wheel, W', on the shaft V'. The rod extends rearward and upward on 90
about an angle of forty-five degrees, and it is provided on its outer end with a crank, W'', near the driver's seat Y', whereby said crank is accessible to the driver when seated. The rear end of the rod W may be suitably mounted 95
and supported by any convenient form of arm or bracket.

As there is often a furrow along the side of hedges, and it being desirable to maintain a uniform height of the top cutter-bar, P, the 100
following mechanism is devised to meet this emergency: The small wheel A' is journaled in a vertical piece, A''. To said piece is secured a right-angled projection, A'.

A^3 are vertical flanged guides secured to the side of standards B. These guides permit of a vertical adjustment of the piece A^2 therein.

B^3 is a lever, secured at its lower end to the right-angled piece A^4 . Said lever is fulcrumed to a short arm, B^2 .

B^4 is a notched standard on the rear cross frame-piece. Said standard is provided with a lever-retaining frame-piece, B^5 .

10 B^6 is a spring on the lever for holding the same in any one of the notches.

The inner end of the cutter-bar P is hinged to one end of the cross-piece Q. A chain, C', is secured at one end to said bar. A pin, C'', is fixed in the top of the cross-piece Q. The chain is adapted to engage said pin by any one of its links, whereby the angle of inclination of the cutter-bar may be adjusted.

The operation of the device is as follows:

20 By rotating the rod W the worm W^3 thereon, through the medium of the worm-wheel W^4 , rotates the shaft V^3 . The cogs V^2 on said shaft elevate or lower the rack-bars V. When said rack-bars are moved vertically, the top 25 horizontal bars, U, Q, Q', Q'', and Q''', and the mechanism mounted thereon, are also moved. The cutter-bars are also moved with said bars and mechanism. The shaft Z is longitudinally grooved on its upper side. Said 30 shaft is provided with a bevel gear-wheel, H. Said shaft and wheel are united by key or spline. The wheel is movable on the shaft. When the adjustable frame is raised or lowered, the wheel H is moved on its shaft, so as 35 to conform to the changed position. The object of the adjustable frame is to raise and lower the cutter-bars.

Having thus described my invention, what I claim, and desire to secure by Letters Patent, 40 is—

1. The combination, with the main frame having fixed vertical standards thereon, of a supplementary frame provided with vertical and horizontal cutter-bars, said frame being 45 vertically adjustable on said standards, where-

by the cutter-bars may be raised and lowered, substantially as specified.

2. The combination, with the main frame having fixed standards thereon, of a vertically-adjustable frame provided with cutter-bars, both 50 vertical and horizontal, the horizontal cutter-bar being hinged to the adjustable frame and provided with means, substantially as specified, for varying the angle of inclination of said bar and securing the same in any desired 55 position, substantially as set forth.

3. The combination, with the main shaft E, of the bevel gear-wheels F X, H I, and L L', and of the shafts to which said wheels are respectively secured, of the crank-wheels M and N' 60 and their pitmen S T, and of the vertical and horizontal cutter-bars, all arranged and operated substantially as described, and for the purposes set forth.

4. The main shaft E, bevel gear-wheels F X, H I, and L L', the shafts to which said wheels are respectively secured, the crank-wheels M and N', and pitmen S T, the gear-wheel H being vertically movable on its shaft, in combination with a vertically-adjustable frame, substantially as described, and for the purposes 70 set forth.

5. The main shaft E, bevel gear-wheels F X, H I, and L L', and the shafts to which said wheels are respectively secured, the gear-wheel H being vertically movable on its shaft, and the vertically-adjustable frame provided with 75 rack-bars V, in combination with the shaft V^3 , provided with cogs and a worm-wheel, as specified, and the crank-rod W, provided with 80 the worm for engaging the worm-wheel, substantially as set forth.

In testimony that I claim the foregoing I have hereunto set my hand this 14th day of January, 1886.

JOHN P. HILEMAN.
